UNITED STATES PATENT OFFICE.

CAESAR PANZERI, OF BROOKLYN, NEW YORK.

WALL-PAPER CUTTING AND PASTING DEVICE.

1,426,667.

Specification of Letters Patent. Patented Aug. 22, 1922.

Application filed October 29, 1920. Serial No. 420,409.

To all whom it may concern:

Be it known that I, CAESAR PANZERI, a subject of the King of Italy, residing at Brooklyn, county of Kings, and State of New York, have invented certain new and useful Improvements in Wall-Paper Cutting and Pasting Devices, of which the following is a specification.

This invention relates to a device for use 10 in papering walls, having more particular reference to a device by which the paste may be applied to the paper and the latter cut into any desired width.

The invention has for a general object to 15 provide a device whereby the work of applying the paper may be facilitated.

More specifically speaking the invention has for an object to provide a device in 20 which the paper may be either pasted alone, or pasted and cut in the one operation, as desired.

For further comprehension of the invention, and of the objects and advantages thereof, reference will be had to the following description and accompanying drawings, and to the appended claims in which the various novel features of the invention are more particularly set forth.

Fig. 1 of the drawings is a plan view of a 30 device constructed according to the invention, the cover being removed.

Fig. 2 is a vertical section on the line 2—2 of Fig. 1, showing the cover in place.

Fig. 3 is a vertical section on the line 3—3 35 of Fig. 2.

Fig. 4 is an enlarged vertical section on the line 4—4 of Fig. 2.

Fig. 5 is a detail longitudinal view, partly 40 in section, of the roll which carries the cutter.

Fig. 6 is an end view thereof.

Fig. 7 is a detail fragmentary elevation showing the means for holding the free end of the arbor for the roll of paper.

Fig. 8 is a transverse section on the line 45 8—8 of Fig. 7.

As here embodied the device comprises a box 1 which is provided with a removable cover 2. This box is separated by a partition 3 into a pair of compartments 4 and 5, the former being adapted to contain a paste applying roll 6. This roll may be constructed in any suitable manner and is here shown as provided with trunnions 7 engaging in

downwardly slotted bearing elements 8 at 55 opposite sides of the box, the roll being thus easily removable from the box when desired. The cover may be provided with the downwardly extending fingers 9 adapted to engage the roll 6 to hold it against movement 60 when the device is being carried from one place to another. The compartment 4 is adapted to contain the paste, into which the roll 6 dips.

The compartment 5 is adapted to receive 65 the roll of paper to be treated, an arbor or mandrel 10 being carried in a trough 11 to receive the roll, the trough 11 being adjustable longitudinally so as to vary the position of the roll therein with respect to the cutting 70 knife, as will be presently pointed out. As here shown the trough 11 is slidably mounted in a second trough element 12 which latter is open at both ends and extends completely from side to side of the box, the side 75 walls of the latter being cut away to receive the ends of this trough. This stationary trough 12 may be removably mounted in place, being here shown as provided with a pair of fixed depending plates 13 adjacent 80 the ends thereof which engage the inner faces of the walls of the box, the trough being held in place by frictional engagement. The trough 11 is held against vertical movement by the co-acting angular guide elements 14 at the upper side edges thereof.

To provide for placing of the roll of paper on the arbor 10 the latter is hinged at one end as at 15 to swing vertically, its opposite end engaging in a slot 16 (Fig. 7) in 90 a transverse strap 17 extending across the trough 11 adjacent the opposite end thereof. The arbor is held against displacement from this slot by means of a sliding ferrule 18 on the strap 17 which is slotted as at 19 to take 95 over the arbor, and is provided with a finger bar 20, the ferrule having a frictional sliding fit on the strap. Mounted on the arbor 10 toward the hinged end thereof is an end-plate 21 which is adjustably held thereon by 100 a set screw 22.

Suitably arranged adjacent one side of the trough 12 is a double scale 23, the numbers on one scale running in opposite directions to those on the other scale, this double 105 scale being here shown as arranged on a strip 24 secured to and extending along one side of the trough 12.

Arranged adjacent the opposite side of the trough 12 is the cutting device, which is mounted and constructed as follows: A pair of arms 25 are hinged at one end as at 26 to the opposite walls of the box 1 and have a roller 27 mounted on the opposite ends thereof. A second roller 28 is mounted under the roller 27, being held in the upper ends of a pair of posts 29 slidably on the walls of the box and guided by the head screws 30 taking through vertical slots 31 in the posts into the walls of the box. This roller 28 is pressed upwardly by a pair of coiled expansion springs 32 which surround a pair of pins 33 fixed in the bottom of the box and bear between the said bottom of the box and outturned feet 34 on the posts 29. To hold the top roller 29 against the pressure of the springs 32 a pair of hooks 35 are mounted on the walls of the box and take over pins 36 on the arms 25. The top roller is adapted to carry the cutting element which consists of a sharpened disk 40, and to provide for cutting either side of the paper as desired the roller is adapted to have this cutter mounted on either end thereof. As here shown the roller 27 has a pair of trunnions 41 (Fig. 5) at opposite ends thereof and is formed with detachable end pieces 42 which fit snugly on the trunnions, the cutter being received between either of these end pieces and the main body of the roller as desired, the latter having pins 43 projecting from opposite ends thereof into sockets 44 in the end pieces 42, the cutter 40 having suitable apertures through which the pins pass, thereby ensuring of the main body of the roller, the cutter, and the end pieces all rotating in unison. One of the trunnions 41 may have a squared end 41' to receive a handle for rotating the roller. The roller 28 is formed with peripheral grooves 46 to accommodate the cutter 40.

The manner of use of my improved device is as follows: The cover 2 being removed, the roll of paper, indicated at 50, is placed on the arbor 10, a supply of paste being placed in the compartment 4. The end plate 21 is adjusted to confine the roll between itself and the strap 17. The cutter 40 is placed on the end of the roller 27 adjacent the side of the paper which is to be cut. The manner of changing the cutter from one end of the roller 27 to the other will be apparent, the arms 25 being swung back and one of them sprung outwardly off its trunnion, the end pieces 42 being pulled off the trunnions, the cutter changed from one end to the other, the end pieces replaced, and the arm again sprung over the trunnion. It will be noted that the main body of the roller 27 is so arranged, and of such a length, that the cutter 40, when in position 65 is opposite the zero mark on the scale which reads from that side of the box toward the other. To position the roll then for cutting to the desired width the trough 11 is moved in its support 12 until the opposite side of the paper to that on which the cut is to be made is in juxtaposition to the number on the scale indicating this width. In Fig. 1 of the drawings the roll is shown arranged to be cut to a width of seventeen inches. The paper is then led between the rollers 27 and 28 backward over the paste roll 6 and under a guide roller 51, being cut to the desired width and having the paste applied thereto, and leaving it ready for application to the wall. When the paper does not require cutting it may be led directly over the pasting roll 6 from its supporting arbor 10. When the paper is to be cut on the side thereof opposite to that indicated in Fig. 1 the cutter 40 will be changed to the opposite end of the roller 27, the trough 11 moved in an opposite direction until the end plate 21 registers with the proper number on the other scale, with the zero mark of which the cutter is now registering.

To hold the cover 2 in place hooks such as 60 may be provided, the cover also having pins 61 thereon which project into suitable borings 62 in the box 1.

Having thus described my invention what I claim as new and desire to protect by Letters Patent of the United States is as follows:

1. In a device of the class described, a box, a paste applying roll, a shaft to support a roll of paper, a cutter adjacent said shaft, a longitudinally adjustable support for said shaft, and means to abut the end of the roll of paper adjustably mounted on said shaft.
2. In a device of the class described, a paste applying roll, a paper supporting roll, a cutter roll having a main central portion and detachable end portions, pins carried by one of said portions and adapted to engage cooperating recesses in the other portion, and a circular cutter blade provided with apertures adapted to be engaged by said pins, whereby said cutter may be mounted adjacent either end of said cutter roll.
3. In a device of the class described, a paste applying roll, a shaft to support a roll of paper, means to adjust said shaft longitudinally, a cutter adjacent one end of said shaft, a scale adjacent the shaft, and means to abut the ends of roll of paper fixed to said shaft and adapted to cooperate with said scale, the relation between said scale and cutter being so fixed that the abutting means will indicate directly upon the scale the width of the paper when cut.
4. A device of the class described comprising a box, a paste applying roll mounted therein, a trough adapted to support a roll

of paper, said trough being adjustable longitudinally of itself in said box, and a cutter arranged adjacent said trough.

5. A device of the class described, comprising a box, a paste applying roll mounted therein, a trough adapted to support a roll of paper, said trough being adjustable longitudinally of itself in said box, and a cutter arranged adjacent said trough, said cutter comprising a circular blade, and means to support said cutter comprising a hinged arm pivoted to said box on the end of which said blade is mounted.
10. A device of the class described comprising a box, a paste applying roll mounted therein, a trough adapted to support a roll of paper, said trough being adjustable longitudinally of itself in said box, an arbor in said trough, a plate on said arbor adjustable therealong, a pair of rollers
15. A device of the class described comprising a box, a paste applying roll mounted therein, a trough adapted to support a roll of paper, said trough being adjustable longitudinally of itself in said box, an arbor in said trough, a plate on said arbor adjustable therealong, a pair of rollers
20. A device of the class described comprising a box, a paste applying roll mounted therein, a trough adapted to support a roll of paper, said trough being adjustable longitudinally of itself in said box, an arbor in said trough, a plate on said arbor adjustable therealong, a pair of rollers

mounted adjacent said trough, a cutter carried by one of said rolls, and resilient means pressing said rollers together.

7. A device of the class described, comprising a box, a paste applying roll mounted therein, a trough adapted to support a roll of paper, said trough being adjustable longitudinally of itself in said box, an arbor in said trough, a plate on said arbor adjustable therealong, a pair of rollers
25. A device of the class described, comprising a box, a paste applying roll mounted therein, a trough adapted to support a roll of paper, said trough being adjustable longitudinally of itself in said box, an arbor in said trough, a plate on said arbor adjustable therealong, a pair of rollers
30. A device of the class described, comprising a box, a paste applying roll mounted therein, a trough adapted to support a roll of paper, said trough being adjustable longitudinally of itself in said box, an arbor in said trough, a plate on said arbor adjustable therealong, a pair of rollers
35. A device of the class described, comprising a box, a paste applying roll mounted therein, a trough adapted to support a roll of paper, said trough being adjustable longitudinally of itself in said box, an arbor in said trough, a plate on said arbor adjustable therealong, a pair of rollers

In testimony whereof I have affixed my signature.

CAESAR PANZERI.
